(57) **CLAIM**

The ornamental design for a lawn mower stand, as shown and described.

DESCRIPTION

FIG. 1 is a front, top perspective view of a lawn mower stand, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, top perspective view of the lawn mower stand in an unfolded state.

The dashed broken lines in the figures are for the purposes of illustrating portions of the lawn mower stand, which form no part of the claimed design.
